UNITED STATES PATENT OFFICE.

RUDOLPH ANDERS, OF BRIDGEPORT, CONNECTICUT.

AIRSHIP.

1,025,106.

Specification of Letters Patent. Patented Apr. 30, 1912.

Application filed November 25, 1911. Serial No. 662,282.

To all whom it may concern:

Be it known that I, RUDOLPH ANDERS, a citizen of the United States, residing at Bridgeport, in the county of Fairfield and State of Connecticut, have invented a new and useful Airship; and I do hereby declare the following to be a full, clear, and exact description of the invention, such as will enable others skilled in the art to which it appertains to make and use the same.

This invention belongs to the art of aviation, and it relates particularly to a new and useful aeroplane of the bi-plane type.

The principal object of the invention is the provision of a simple, efficient and practical improved biplane, in which there is involved novel features of construction.

One of the features of this improved biplane is the lowering and elevating plane, which is centrally pivoted and so manipulated as to direct the biplane up or down, while the rudder in the rear is manipulated, so as to guide the craft to the right or the left.

The invention comprises further features and combination of parts, as hereinafter set forth, shown in the drawings and claimed.

In the drawings: Figure 1 is a view in side elevation of a biplane constructed in accordance with the invention. Fig. 2 is a plan view. Fig. 3 is a transverse sectional view on line 3—3 of Fig. 2. Fig. 4 is a transverse sectional view on line 4—4 of Fig. 2. Fig. 5 is a detail view of the means for manipulating the elevated plane. Fig. 6 is a sectional view on line 6—6 of Fig. 5. Fig. 7 is a detail view of the connection between the rudder and its operating means.

Referring to the drawings 1 designates a frame which is substantially triangular in plan view, and comprises the upper and lower portions 3 and 4. These upper and lower portions are braced relatively with regard to one another by the vertical bars 5 and the brace rods 6. This frame may be constructed of any suitable material. The upper and lower portions of the frame are covered with areas of canvas or other suitable material 7, thus providing the upper and lower planes. On the upper surface of the lower portion of the frame is a platform of any suitable material 8, which supports any suitable type of engine or other motor 9 having the usual drive shaft 10. Mounted in bearings on the platform, for-

wardly and rearwardly of the frame are shafts 11 and 12. These shafts are provided with suitable clutch connections 13 with the drive shaft of the engine. The clutch connections are of a type, such as will permit the shafts 11 and 12 to be thrown in and out of gear with the drive shaft of the engine. Mounted on the rear end of the shaft 12 is a propeller 14. The forward end of the shaft 11 is provided with a sprocket 15, which is geared to the sprocket 16 by the chain 16^a of the shaft 17, so as to impart motion thereto. On the shaft 17 is a propeller 18, which is larger than the propeller 14. The platform is provided with a series of seats, one to be used by the operator while the others are for passengers. These seats are designated by the numerals 19 and 20.

An elevating plane 21 is provided, which extends transversely of the craft, and is pivoted in the forward portion thereof, as at 22 so as to oscillate, whereby the craft may be directed downwardly or upwardly. The pivot shaft 22 of the elevating plane is journaled in bearings of the standards 23. Projecting upwardly from the pivot shaft 22 is an arm 24, to which is connected a rod 25, which threads through a wheel 26, as shown. This wheel 26 is mounted to rotate in bearings 27 of the frame 28. When this wheel is rotated in one direction or the other, the rod 25 is reciprocated, which in turn oscillates the elevating plane.

The rudder 29 is hingedly connected to the frame of the craft, as at 30, and is also provided with a laterally extending braced arm 31, which connects with the rod 32, which also threads through a wheel 33 similar to the wheel 26. The wheel 33 revolves in the frame 34, and when manually manipulated the rudder 29 is thrown to the right or the left, by virtue of the rod connection.

Extending longitudinally of the frame and downwardly therefrom, is what may be termed the equilibrium plane or keel 35, which is hinged to the frame. This keel may be oscillated by the means 36, 37 and 38. The parts 36, 37 and 38 are similar to the mechanism for manipulating the elevating plane. The object for permitting the keel to be oscillated, is to dispose the craft in such a position as to cause it to make long curved sweeps, or short ones.

From the foregoing it will be noted that,

there has been devised a novel, simple and efficient biplane, and one which has been found practical.

The invention having been set forth, what is claimed as new and useful is:

1. In an aeroplane, a frame of an elongated triangular contour in plan and having upper and lower spaced apart oppositely disposed planes corresponding in shape to the contour of the frame, an elevating elongated equilibrium plane extending transversely of the frame and fulcrumed therein substantially midway of its width, and located approximately centrally between the upper and the lower frames, with substantially equal correspondingly shaped portions extending laterally upon either side of the frame, a keel equilibrium plane of elongated substantially triangular contour fulcrumed under the frame substantially midway of its width and adapted to oscillate laterally, a rudder equilibrium plane fulcrumed in a vertical position substantially at the rear of the frame to oscillate laterally, and like mechanisms, each of which is capable of being operated independently, to independently oscillate each equilibrium plane.
2. In an aeroplane, a frame of an elongated triangular contour in plan and having

upper and lower spaced apart oppositely disposed planes corresponding in shape to the contour of the frame, an elevating elongated equilibrium plane extending transversely of the frame and fulcrumed therein substantially midway of its width, and located approximately centrally between the upper and the lower frames, with substantially equal correspondingly shaped portions extending laterally upon either side of the frame, a keel equilibrium plane of elongated substantially triangular contour fulcrumed under the frame substantially midway of its width and adapted to oscillate laterally, a rudder equilibrium plane fulcrumed in a vertical position substantially at the rear of the frame to oscillate laterally, and like mechanisms, each of which is capable of being operated independently, to independently oscillate each equilibrium plane, and a propelling mechanism for the aeroplane.

In testimony whereof I have signed my name to this specification in the presence of two subscribing witnesses.

RUDOLPH ANDERS.
